(57) **CLAIM**

The ornamental design for a chisel honing guide blade carrier, as shown and described.

DESCRIPTION

FIG. 1 is an isometric view of the top, front and right side of the chisel honing guide blade carrier;

FIG. 2 is an isometric view of the bottom, front and left side of the chisel honing guide blade carrier of FIG. 1;

FIG. 3 is a top view of the chisel honing guide blade carrier of FIG. 1;

FIG. 4 is a bottom view of the chisel honing guide blade carrier of FIG. 1;

FIG. 5 is a front view of the chisel honing guide blade carrier of FIG. 1;

FIG. 6 is a rear view of the chisel honing guide blade carrier of FIG. 1;

FIG. 7 is a right side view of the chisel honing guide blade carrier of FIG. 1; and,

FIG. 8 is a left side view of the chisel honing guide blade carrier of FIG. 1.

The evenly dotted broken lines in the drawings illustrate unclaimed features of the claimed design and form no part of the claimed design.

1 Claim, 8 Drawing Sheets
